Hausman & Baum

UNITED STATES PATENT OFFICE.

ELLWOOD IVINS, OF PHILADELPHIA, PENNSYLVANIA.

BUMPER BAR FOR AUTOMOBILES.

Application filed March 3, 1925. Serial No. 12,925.

To all whom it may concern:

Be it known that I, ELLWOOD IVINS, a citizen of the United States, residing in Philadelphia, Pennsylvania, have invented certain 5 Improvements in Bumper Bars for Automobiles, of which the following is a specification.

The object of my invention is to improve the construction of bumper bars, which are 10 used on automobiles and like vehicles, so that the polished surface of the bar will not become disfigured.

The present method of making bumper bars is to make the bars of iron or steel tubes 15 and to electro-plate the bars with nickel.

The objection to this method of manufacture is that the thin plating of nickel becomes detached from the bar, exposing the iron or steel base, when the bar comes in 20 violent contact with an object, or is scratched, or otherwise injured, making the bar unsightly.

In the accompanying drawings:

Fig. 1 is a perspective view of my improved bumper bar;

Fig. 2 is a sectional view of one end of the bar; and

Fig. 3 is a transverse sectional view on the line 3—3, Fig. 2.

The bar 1 is made of a heavy, drawn seamless tube of iron or steel, of any desired 30 diameter. Over the bar 1 is drawn a seamless tube 2 of nickel alloy. The two tubes

are closely associated, as the drawing action makes the nickel alloy tube adhere to the 35 iron, or steel tube. The nickel alloy tube is heavier than the plating heretofore used and does not crack, nor does it expose the iron base, if scratched. If the nickel alloy tube is cut so as to expose the base, the nickel 40 alloy tube is in no way affected.

The tube can be open at each end, or it can be provided with an ordinary cap, if desired, which is ornamental in any suitable manner.

The bumper brackets 4 can be of any form desired. When they are clamped to the bar, as in Fig. 2, they engage the nickel tubular shell and can be clamped tightly thereon without damaging the shell, as the nickel 50 yields under pressure, and does not crack to expose the base metal.

I claim:

1. A bumper bar for automobiles, and other vehicles, consisting of a tube of iron 55 or steel enclosed within a drawn tube of nickel alloy.

2. A bumper bar for automobiles, and other vehicles, consisting of a drawn steel tube, over which is drawn a tube of nickel 60 alloy.

3. A bumper bar for automobiles, and other vehicles, consisting of a drawn, seam- 65 less steel tube, enclosed within a drawn, seamles tube of nickel alloy.

ELLWOOD IVINS.
